UNITED STATES PATENT OFFICE.

GUSTAV SWENSON, OF NEW YORK, N. Y., ASSIGNOR TO GEORGE PETERSON, OF NEW YORK, N. Y.

CONCRETE-MOLD CONSTRUCTION.

1,388,904.

Specification of Letters Patent. Patented Aug. 30, 1921.

Application filed March 16, 1921. Serial No. 452,680.

To all whom it may concern:

Be it known that I, GUSTAV SWENSON, a citizen of the United States, residing in the city, county, and State of New York, have 5 invented an Improvement in Concrete-Mold Construction, of which the following is a specification.

This invention relates to concrete mold construction and more particularly to improvements in means for adjustably clamping the molds into the desired form.

One of the objects of the invention is to provide readily adjustable and detachable means for locking together two members 15 which meet at an angle. A further object is to apply this locking means to clamps which may be used to hold concrete molds in their desired shape. The molds are preferably surrounded by angular retaining members, 20 their ends overlapping sufficiently to give the desired size and the locking members applied to these ends to fix them firmly together. When angular retaining members are used, at least one-half of the angles are 25 always fixed and, in the case of square columns, it will merely be necessary to adjust one angle. This greatly facilitates the assembling of the mold. The overlapping ends permit wide variations in size, since the 30 angular retaining members may be made considerably larger than required for the particular mold.

Another object of this invention is to provide a simple and practical means for assembling concrete molds for columns, beams, pilasters, etc., that can be readily disassembled when it is desired to transfer the mold to another part of the building; to also provide a mold that is made up of relatively 40 light parts, that may be readily moved from one part of the building to another.

This invention aims to eliminate the difficulties encountered in the present means of construction by constructing angular retaining members of a standard design and by applying a readily adjustable and detachable locking means to the ends of these members. In the case of square columns, two of the 45 angles are fixed and it becomes comparatively easy, therefore, to fix the other angle. These clamping members are readily adaptable to molds of various sizes and they combine lightness with facility of operation and eliminate the necessity of the inefficient 50 means heretofore used. It will be readily

seen that the application of an improved clamping device of the character described, where the molds are used repeatedly, will result in speeding up the work and decreasing the amount of labor required.

Other objects will be in part obvious or in part pointed out hereinafter.

In the accompanying drawings in which is shown one embodiment of this invention by way of example and in which similar reference characters refer to similar parts throughout,

Figure 1 is a perspective, showing the improved clamping means as applied to square column molds,

Fig. 2 is an end elevation of the device as applied to beams, pilasters, etc.,

Fig. 3 is an end view of a hexagonal column mold as held in place by the improved clamping means,

Fig. 4 is an end view showing a method of holding the outer side of a mold in an upright position,

Fig. 5 is an end view of a beam or a pilaster showing the application of an angular 80 retaining member,

Fig. 6 is a detailed perspective showing the construction and application of the improved locking means, and

Fig. 7 shows another form of the tie member.

Referring more particularly to Fig. 1, 10 designates the mold forming members, which may be ordinary boards of suitable dimensions for the mold. When it is desired 90 to increase or decrease the size of the mold, it is merely necessary to change the number or size of the mold forming members accordingly. The angular retaining members 11 are made of any ordinary metal of sufficient strength to perform their function and are provided at each of their ends with a series of notches or seats 12, coöperating with the tie member 13, and key 14 to clamp the mold forming members in position. The 100 tie member 13 as more fully shown in Figs. 6 and 7, consists of a pair of legs 15 formed by the slot 16.

These legs are bent at their free ends into the abutments 17 and hooks 18 which receive 105 the key 14. It will be seen from the figures that the members 20 and 21, which may or may not be angled are received in the slot 16 and are engaged respectively by the bottom of the slot and by the edge of the tapered key 110

14 and are thus firmly locked together against any outward stresses exerted by the members 10. By choosing different seats to be engaged by the tie member, relatively 5 large adjustments in size may be obtained. Since the key 14 is tapered sufficiently to permit small adjustments which cannot be made by going from one seat to another, delicate adjustments may be made for any 10 change in size. To secure the best results, the key should be tapered enough to give a maximum adjustment by the key equal to or greater than that given by moving the tie member the distance of one seat. It is also 15 to be noted here that since two of the angles are fixed, it is only necessary to adjust one other angle.

Fig. 3 shows the invention as applied to a hexagonal mold in which the outer angular 20 retaining members 11 have an angle of 120° instead of 90°, as in the case of a square column. It is obvious from this that a mold of any shape may be constructed by providing the proper shaped angular retaining members. In the instance of a mold with 25 an odd number of sides, it is necessary to have one straight member to replace an angular retaining member 11. Since molds are usually in the form of rectangles, squares 30 or other regular polygons, the angular retaining members 11 may be manufactured from a standard design and be adaptable to molds of various sizes, thus eliminating special clamps or yokes for the various molds 35 used throughout the building.

Referring to Figs. 2 and 5, wherein the invention is shown as applied to beams and pilasters, which are integral with a concrete floor or wall, in these figures the beams and 40 pilasters are shown as rectangular, merely for convenience. They obviously may be in many other forms. In Fig. 2, a pair of straight members are fixed in any desired manner, as by the flanges 23 and bolts 24 to the wall or floor molds 26. The free ends 45 of the members 22 are provided with the usual seats 12 and connected by the straight member 25. This member is likewise provided with the usual seats and has each 50 of its ends locked to one of the members 22 by the tie members 13, hereinbefore described. Fig. 5 shows the straight member 25 and one of the members 22 replaced by the angular retaining member 27. Fewer 55 parts are required for this method of construction, but it requires screw adjustment between the angular retaining member 27 and the wall 26, while in the other construction all the adjustments may be made through the 60 tie members 13. This screw adjustment can be accomplished in any desired manner, as by having the end 28 of the angular retaining member threaded an amount sufficient to take care of the necessary variations in 65 size and provided with a washer 29 and a

nut 30. This form permits the use of one angular retaining member, thereby fixing one angle of the pilaster or beam and facilitating the adjustment in shape, as hereinbefore noted.

In the construction of buildings, applications for inverted retaining members to withstand longitudinal stresses are quite frequently found. A typical example of this is shown in Fig. 4 where it is desired to retain the member 31 in an upright position. To do this the member 32 is extended beyond the mold and provided with the seats 12 and the pin 33 as shown. A member 34 provided with the serrations 37 70 to prevent slipping is connected through the joint 35 to the inverted member 36 which has a series of seats 12 along its free end. The free end of the inverted retaining member 36 rests upon the pin 33 and is locked 75 by the tie member 13 and the key 14 to the member 32, to resist the longitudinal stress in the inverted member 36 set up by the member 31. Thus it will be seen that the invention is readily adaptable to the resisting of longitudinal as well as transverse 80 stresses as hereinbefore described.

Fig. 7 shows another illustrated embodiment of the tie member 13. Its operation is the same as that shown in Fig. 6, its construction being such as to embody greater strength. A slot 38 is preferably punched in a flat piece of metal, the slot being closed by the ends 39. These ends are then bent together, as shown, to form the abutments 90 40 and the legs 41. The bending together of the ends 39 also forms the loop 40 in which the key 14 may be seated, instead of in the hooks 18, as shown in the other embodiment. It will be seen from a comparison 95 of the tie members of Figs. 6 and 7, that to cause the embodiment in Fig. 6 to release its hold, it is necessary for the hooks 18 to give way. In the loop structure, it is necessary that a pair of the legs 41 break: 100 110 This form is particularly adaptable where great strength is required. However, it is found that the tie member provided with hooks is the easier to construct and, under ordinary conditions, it is sufficiently strong 115 to perform its function. Each has its field of application as hereinbefore noted.

It will be seen that the above locking and clamping means may be easily manufactured from readily obtainable materials of 120 commercial section, also that the same clamping means may be used for various sizes of molds. The tapered key provides for relatively small adjustments of size or shape and the seats permit relatively large 125 adjustments. Thus the device will permit either delicate or rough adjustments and the two may be combined to give a very precise adjustment with any change in size. The device combines strength with lightness 130

and permits quick fixing or removal of the clamping means when the mold is being constructed or detached. It will be noted, therefore, that there is provided in this invention, 5 a structure of simple and inexpensive construction and highly efficient action.

As various embodiments may be made in the invention above set forth, and as many changes may be made in the structure hereinbefore described, it is to be understood that all matter herein set forth is to be interpreted as illustrative and not in a limiting sense.

I claim as my invention

15 1. In a construction of the class described, in combination, a plurality of mold forming members, a plurality of retaining members, a series of seats on each of said retaining members, a tie member having one end adapted to engage a seat on one of said members and having the other end in the form of a seat, a tapered key coöperating with said seat on said tie member and a seat on one of said retaining members to hold the two of 25 said retaining members together.

2. In a construction of the class described, in combination, a plurality of mold forming members, a plurality of members serrated at their outer edges, a tie member having one end adapted to engage said serrated portions of one of said members and having the other end in the form of a seat, a tapered key adapted to fit into said seat and to engage the serrated portions of another of said members 35 to hold the two of said members together.

3. In a construction of the class described, in combination, a plurality of mold forming members, a plurality of angular retaining members provided with serrated portions on 40 the outer edges and near the ends of said angular retaining members, a tie member having one end adapted to engage a serrated portion of one of said angular retaining members and having the other end of said 45 tie member in the form of a seat, a key adapted to coöperate with said seat and a serrated portion of another of said retaining members to hold the two of said angular retaining members together.

50 4. In a construction of the class described, in combination, a plurality of mold forming members, a pair of angular retaining members, a series of seats on each of said angular retaining members, a tie member slotted to receive the ends of said pair of angular retaining members between the legs formed by said slot, and adapted to engage a selected 55 seat on one of said angular retaining members, means integral with said legs forming

a pair of abutments, one on each of said legs, 60 and a tapered key adapted to be seated between said abutments and a selected seat on the other of said retaining members to lock the ends of said retaining members together.

5. In a construction of the class described, in combination a plurality of mold forming members, a pair of members, a series of seats on each of said members, a tie member slotted to receive the ends of a pair of said members, between the legs formed by said slot, 70 said tie member engaging the selected seat on one of said members, means integral with said legs forming a pair of abutments, one on each of said legs, and a tapered key adapted to be seated between said abutments and 75 a selected seat on the other of said members to lock the ends of said members together.

6. In a construction of the class described, in combination a plurality of mold forming members, a plurality of angular retaining members arranged end to end in a geometric figure about said mold forming members, a series of seats near the ends of each of said angular retaining members, a tie member slotted to fit over the ends of a pair of said 80 angular retaining members and to engage a selected seat on one of said members, a pair of abutments integrally formed with said tie member and a tapered key adapted to be seated between said abutments and a selected 90 seat on the other of said pair of angular retaining members thereby locking the two ends of said angular retaining members together.

7. In a construction of the class described, 95 in combination a plurality of mold forming members, a plurality of angular retaining members arranged end to end about said mold forming members, a series of seats on the outer edges of said angular retaining 100 members, a tie member slotted to fit over the ends of two adjacent angular members and to engage one of said seats on one of said angular retaining members, a pair of abutments integrally formed with said tie 105 members, a tapered key to coöperate with said abutments and one of said seats on an angular retaining member to directly crowd one angular member toward the other and to adjustably lock adjacent members together, 110 a relatively large adjustment being permitted by selecting different seats and a relatively small adjustment being made by the further insertion of said tapered key.

In testimony whereof, I have signed my 115 name to this specification.

GUSTAV SWENSON.
